UNITED STATES PATENT OFFICE.

GEORGE H. HURTEAU, OF AURORA, ILLINOIS, ASSIGNOR TO ELECTRIC SERVICE SUPPLIES COMPANY, OF PHILADELPHIA, PENNSYLVANIA, A CORPORATION OF PENNSYLVANIA.

GEAR-CASE.

1,174,072.

Specification of Letters Patent.

Patented Mar. 7, 1916.

Application filed March 28, 1913. Serial No. 756,910.

To all whom it may concern:

Be it known that I, GEORGE H. HURTEAU, a citizen of the United States, residing at Aurora, in the county of Kane and State of Illinois, have invented certain Improvements in Gear-Cases, of which the following is a specification.

My invention is designed primarily to provide a gear case that will more satisfactorily protect the motor or driving mechanism suspended under cars and withstand the severe service attending this use.

10 Gear cases carried beneath electric cars are subject to constant vibration and severe 15 strains under normal conditions of use, and are liable to receive shocks or blows due to rocks or other obstacles on the track, the effects of which have been, with constructions heretofore used, to cause rapid deterioration of such cases and to permit injury 20 to the machinery which it is the function of the cases to protect.

The improvements of my invention are 25 characterized by the combination of parts so as to avoid structural weaknesses, to provide peculiar reinforcement for the case where failure is most liable to occur, and, by the use of peculiar means for preventing movement at the joints, to eliminate shearing strains on rivets and consequent wear 30 and failure.

The peculiar features of my improvements are fully disclosed in the following description and the accompanying drawings in illustration thereof.

In the drawings, Figure 1 is a perspective view of a gear casing made in accordance 40 with my invention; Fig. 2 is a perspective view of a second form thereof; Fig. 3, Fig. 3^a, Fig. 3^b, and Fig. 3^c represent perspective views of successive stages in making the sides of the case; Fig. 4, Fig. 4^a and Fig. 4^b represent perspective views of successive stages in making the periphery strips; Fig. 45 5 is a vertical sectional view taken transversely through a case embodying my improvements; Fig. 6 is a part sectional perspective side elevation of the case shown in Fig. 2; Fig. 7 is a vertical sectional view 50 taken longitudinally through the left end of the case shown in Fig. 6, and Fig. 8 is a vertical sectional view taken longitudinally through the right end of the case shown in Fig. 6.

55 The sides of the case are formed from

steel sheets 1 which are cut to form oval blanks 2 and these blanks are pressed to form pans 3 which are divided longitudinally with the production of the sections 4 having the flanges 4' joined thereto by the sections 4^a of easy curvature, of such character as to avoid straining the metal, the divided parts being symmetrical with reference to the plane of division.

The periphery of the case comprises strips 5 formed from sheet steel plates 5^a having the depressed edges 5' and the hems or in-turned laminations 5^b.

The case is made in separable top and bottom sections, formed by joining right and left hand parts 4 by parts 5, which are fixed together with the parts 4' lying on the parts 5' in abutting relation to the relatively offset central or body part of the strips 5, and with the parts 5' and 5^a sprung by the pressure thereon of the parts 4 so as to substantially conform to the curved sections 4^a, whereby the sides are stayed. Rivets 6 are passed through and draw together the laminated parts 4^b, 5' and 5^a, and spot welds 7 are formed electrically along the edge of the seam to integrally connect the parts 4', 5' and 5^a at the points of welding whereby there is eliminated the relative movement, wear and consequent failure which commonly takes place at the mechanically connected joints of usual cases.

Curved reinforcing plates 8 and 9 are riveted to the upper section of the case against the inner surface of the ends of the periphery strip 5 therein so as to lap the ends of the strip 5 of the other half of the case, and curved reinforcing plates 8' and 9' are riveted to the lower section against the ends of the periphery strip 5 thereof and so as to make butt joints with the respective parts 8 and 9. Longitudinal strips 10 are fixed to the sides 4 of the bottom section of the casing and combine with the inset edges 4^b thereof to provide seats for the sides 4 of the upper half of the case.

As shown in Fig. 1, the two halves of the case are fastened together by the peripheral plates 11 riveted thereon and having the parallel flanges 11' clamped together by the bolts 12; and the case is supported by the brackets 13, 14 and 15 riveted to the upper half thereof.

As shown in Figs. 2, 6, 7 and 8, the two halves of the case are fastened together and

supported by the peripheral plates 16, 17, 18 and 19 riveted thereon and having the parallel flanges 16', 17', 18' and 19' connected and fixed to the frame 20 by bolts 5 21 and 22. In this construction a blow may bend but will not break the case by reason of the manner in which the joints are made, the case remains strong and tight because the spot welding not only reduces the number of rivet holes otherwise required but the rivets are subject to tensile stress only so that usual wear of the metal is avoided, and the use of spot welding in place of continuous welding avoids the deterioration 15 of the metal due to heating in making an all welded joint, hence the combination of spot welding with riveting avoids the defects of an all riveted and of an all welded construction.

20 Having described my invention, I claim:

1. A gear case having sides with inturned flanges, a periphery strip having edges comprising juxtaposed laminations bearing against said sides within said flanges, and means for fixing said flanges and edges together.
2. A gear case having sides with inturned flanges connected therewith by curved sections, a periphery strip having edges with 30 inturned laminations conforming substantially to said curved sections and providing an interior support for said sides, and means for fixing said flanges and edges together.
3. A gear case having sides provided with 35 inturned flanges, a periphery strip having edges lying within said flanges, and mechanical means and spot welds for fixing said flanges and edges together.
4. A gear case comprising a side and a 40 periphery connected by a joint having rivets and spot welds.
5. A gear case having parts connected by alternating rivets and spot welds.
6. A gear case having sides with inturned 45 flanges, a periphery strip having laminated edges within said flanges, rivets passing through said flanges and edges, and spot

welds integrally connecting the laminations of said edges and said flanges.

7. A gear case having sides with inturned 50 flanges, a periphery strip having an offset part against which the edges of said flanges abut and laminated edges lying within said flanges in engagement with said sides, and means for fixing said flanges and edges together.

8. A gear case comprising sides having inturned flanges connected therewith by curved sections, periphery strips having laminated edges within said flanges, said 60 edges being sprung and bearing against said sides, and means for fixing said flanges and edges together.

9. A gear case comprising separable sections having sides with inturned flanges, 65 periphery strips having edges with inturned laminations on which said flanges are fixed, and end plates fixed within said sections against the ends of said strips.

10. A gear case comprising separable sections having sides with inturned flanges, periphery strips having edges on which said 70 flanges are fixed, and end plates fixed within said sections against ends of said strips, the end plates aforesaid forming lap joints 75 with the ends of complementary periphery strips separable therefrom.

11. A gear case comprising separable sections having sides with inturned flanges, periphery strips having edges on which said 80 flanges are fixed, end plates fixed within said sections against ends of said strips, and end plates fixed on said flanges and ends of said periphery strips, said last named end plates having flanges thereon whereby said 85 sections are held together.

In testimony whereof I have hereunto set my name this 15th day of March, 1913, in the presence of the subscribing witnesses.

GEORGE H. HURTEAU.
